[57] CLAIM

The ornamental design for an outdoor light fixture, as shown
and described.

DESCRIPTION

FIG. 1 is a perspective view of an outdoor light fixture,
showing our new design;

FIG. 2 is a front, right side, left side and rear view thereof;

FIG. 3 is a top view thereof; and,

FIG. 4 is a bottom view thereof.

The broken line showing of environmental structure in FIGS.
1 and 4 is for illustrative purposes only and forms no part of
the claimed design.
